DEAD LATCH MECHANISM

Fred J. Russell, Los Angeles, Calif.

Application June 18, 1954, Serial No. 437,605

1 Claim. (Cl. 292—169)

The invention relates to locking devices and has particular reference to a latch mechanism equipped with a dead bolt by means of which manipulation of the latch bolt when the door is locked is prevented by the interposition of a catch behind the latch bolt activated by the dead bolt.

In recent years increased attention has been given to providing dead bolts for use with latch mechanisms ordinarily designed to be unlocked with a key. Employment of dead bolts is essentially for the purpose of minimizing tampering with a lock mechanism so that the latch or lock mechanism once locked cannot be manipulated into an unlocked position by unauthorized persons. In dead locking mechanisms the tendency has been heretofore to build a considerable ruggedness into the mechanism doubtless prompted by the urge to emphasize security. Because of the growing tendency to reduce the size of casings and housings for cylinder lock sets and tubular lock sets, dead bolt mechanisms which have been constructed in an attempt to emphasize security have been complicated to a considerable degree and have necessitated careful machining of close-fitting parts in order to make certain that the dead bolt mechanism operates with the consistency and security expected. The design and construction thus employed heretofore has invariably resulted in an expensive construction which has made the retail price of lock hardware of this type prohibitive economically for a great many installations.

It is accordingly among the objects of the invention to provide a new and improved latch mechanism which incorporates a dead locking feature wherein the mechanism is simple, inexpensive, and at the same time reliably secure.

Another object of the invention is to provide a new and improved latch mechanism featuring a dead bolt mechanism wherein an actuator spring for the dead bolt mechanism is kept light in weight and separated from the remaining portions of the latch mechanism so as to assure positive and secure action of the dead bolt without adding to a material extent to the cost of the mechanism as a whole.

Still another object of the invention is to provide a new and improved combined latch and dead latch device simply and economically constructed but without sacrifice of positive and secure action wherein spring means is adapted to provide tension of different degrees for the dead bolt, the latch bolt, and the operating means.

Still further among the objects of the invention is to provide a new and improved latch and dead bolt combination wherein reciprocatable parts comprise flat elements constructed of inexpensive stock material which are easy to form into interlocking pieces, smooth in their action and secure under all circumstances, the construction being such that the combination can be built inexpensively and therefore made available for many types of installations which heretofore have not been able to be supplied by latch and dead bolt combinations available.

With these and other objects in view, the invention consists in the construction, arrangement and combination of the various parts of the device whereby the objects contemplated are attained, as hereinafter set forth, pointed

2

out in the appended claim and illustrated in the accompanying drawings.

In the drawings:

Figure 1 is a horizontal view of the device as installed in a door partly broken away to show the location of the dead bolt mechanism.

Figure 2 is a longitudinal sectional view of the device with parts in the position occupied when the door is open.

Figure 3 is a longitudinal sectional view taken on the line 3—3 of Figure 2.

Figure 4 is a longitudinal sectional view taken on the line 4—4 of Figure 2.

Figure 5 is a cross-sectional view taken on the line 5—5 of Figure 2.

Figure 6 is a cross-sectional view on the line 6—6 of Figure 3.

Figure 7 is a partial sectional view similar to Figure 2 but showing the condition of the mechanism as it would be with a door closed.

Figure 8 is a view similar to Figure 2 showing the parts in the position they would have as the latch bolt is being retracted by rotation of the knob.

Figure 9 is an exploded view showing the parts respectively of the latch bolt member and dead bolt member.

In the combined latch and dead bolt mechanism chosen for the purpose of illustration there is shown an outer knob assembly 10 and an inner knob assembly 11 secured together by suitable connecting means 12 in a door 13. A spindle 14 extends between the outer and inner knob assemblies. The door is shown closed with respect to a door frame 15 provided with a strike plate 16 and a door jamb 17.

A cylindrical housing 18 has an inner wall 19 at the end which extends into the door 13. The outer end of the cylindrical casing is open as indicated at 20. For convenience the outer end of the housing is provided with a flange 21 adapted to overlie plates 22 by means of which the housing is secured within a bore 23 extending edgewise of the door 13. The bore 23 communicates with a transverse aperture 24 through which the spindle extends.

In the housing 18 is a latch bolt assembly reciprocatably mounted and consisting of a latch bolt head 27 having a customary tapered face 28 adapted to engage the strike plate 16. Attached to the head is a latch bolt shaft 29, the latch bolt shaft being in the form of a flat plate intermediate opposite sides of the bolt. The latch bolt shaft has a rectangular opening 30 intermediate inner and outer ends. The inner end may be bifurcated as a structural convenience providing thereby legs 31 and 32 having a space 3 therebetween. The form of the latch bolt shaft is shown to good advantage in Figure 9.

Cooperable with the latch bolt shaft 29 is an actuator plate 34 having a hooked portion 35 extending through the rectangular opening 30. At the inner end of the actuator plate are lugs 36 against which a cam 37 is adapted to bear when turned either right or left by rotation of the spindle 14. The actuator plate is provided with a slot 38 which permits the actuator plate together with the latch bolt shaft to shift reciprocatably in and out as the latch bolt is withdrawn and released, the slot and space being adapted to admit a post 39 comprising a portion of the connecting means 12.

A relatively heavy coiled compression spring 40 is biased between the inside of the inner wall 19 and a shelf 41 which is part of the actuator plate 34. The spring 40 resists rotation of the operating assemblies and serves to return the actuator plate to an outer position after the latch bolt assembly has been withdrawn.

The latch bolt head 27 and latch bolt shaft 29 are adapted to move independently of the actuator plate 34 so that the head can shift as it strikes the strike plate without the necessity of the operating assemblies rotating.

To resist the motion of the head there is provided a relatively lighter compression spring 42 biased between an inside face 43 of the head and the shelf 41 on the side opposite from the spring 40.

A dead bolt mechanism comprises essentially a dead bolt head 50 which lies adjacent the long side of the latch bolt head 27. At the inner end of the dead bolt head 50, as seen to good advantage in Figure 9, are slots 51 adapted to receive wings 52 extending transversely at the outer end of a dead bolt shaft 53. The dead bolt shaft is also in the form of a flat plate also bifurcated as a structural convenience toward its inner end to provide legs 54 and 55 having a space 56 therebetween. Hooks 57 at the inner ends of the legs 54 and 55 extend inwardly into the space 56. Raised portions 58 and 59 are located intermediate outer and inner ends of the legs and form operating elements of the dead bolt mechanism.

A dead locking blocker 60, illustrated to good advantage in Figure 9, has an inner end portion 61 terminating in lugs 62, the lugs being adapted to extend through appropriate apertures in the inner end wall 19 of the housing. It will be noted that the blocker 60 comprises arms 63 and 64 providing a space 65 therebetween. The arms are adapted to lie on opposite sides of the dead bolt head 50 as shown in Figure 4. At the bases of the arms are raised portions 66 and 67 located so that they are adapted to engage raised portions 58 and 59 at certain positions of adjustment, as illustrated in Figure 2.

A relatively light gage, long compression spring 68 is biased between a spring keeper 69 at the inner end of the dead bolt head and a keeper 70 which extends diagonally outwardly from the inner end portion 61 of the blocker within the space 65. It should be noted that the center line of the spring keeper 69 lies slightly outside of the center line of the lugs 62. Arranged in this fashion the spring 68 when compressed will bow outwardly into contact with the wall of housing 18, thereby altering the application of spring force to a diagonal direction inwardly. The spring pressure thus applied serves to tilt the blocker about the mounting of the lugs on the wall 19 in a counterclockwise direction as viewed in Figure 2 and as viewed also in Figures 7 and 8.

For mounting the housing 18 and its contents in the door there are provided two casing plates 71 and 72. The casing plate 72 may be provided with a hooked end 73 by means of which the casing plate can be hooked to the inner end 19 of the housing. The casing plate 71 also extends through the inner end 19 in a position separated from the casing plate 72 by the interposition of the latch bolt shaft 29, the actuator plate 34, and the dead bolt shaft 53, all of which occupy the space between the casing plates and which in assembled condition serve to hold the casing plates apart at the ends which engage the housing. At opposite ends of the casing plates 71 and 72 suitable rivets 74 are provided to anchor the plates together in separated relationship. Recesses 75 are adapted to receive a post 76 which also forms a portion of the connecting means 12. The casing plates are further provided with apertures 77 for reception of a hub 78 of the cam 37.

In operation the parts in normal position when the door is opened occupy the positions and relationships illustrated in Figures 2, 3 and 4. As there shown the latch bolt head and dead bolt head are both extended outwardly toward the right. In that position, as best seen in Figure 2, the dead bolt blocker 60 lies substantially parallel to the axis of the latch mechanism for the reason that the raised portion 66 is in engagement with the raised portion 58, the raised portion 67 similarly being in engagement with the raised portion 59. In that position the spring 68 urges the dead bolt outwardly. At the same time the spring 42 urges the latch bolt head 27 outwardly. If it be assumed now that the door is swung

to closed position, as indicated in Figure 1, when the latch bolt head 27 strikes the strike plate, it will move toward the left against the spring 42 until it reaches the conventional opening in the strike plate at which location it will swing back again to outer position as illustrated in Figure 1. As the latch bolt head 27 is being shifted from right to left, it will carry with it the dead bolt. This occurs because wings 52 of the dead bolt shaft 53 lie behind the latch bolt head 27 so that the latch bolt head pushes against the wings which in turn engage the dead bolt head 50 causing the dead bolt head to be carried with the latch bolt head toward the left against the compressive tension of the spring 68.

However, when the latch bolt head moves back to its initial position in the conventional recess in the strike plate 16, the dead bolt head will be held depressed in the position shown in Figure 1. Hence, the spring 68 will remain contracted. Moreover, as the latch and dead bolts move inwardly, the dead latch shaft moves toward the left. During initial movement the raised portions 66 and 67 remain in engagement with the raised portions 58 and 59 until a flat side 80 of the latch bolt head 27 moves past the outer ends of the arms 64. Thereafter when the raised portions disengage with continued movement of the dead bolt shaft toward the left, the blocker 60 will continue to occupy the position illustrated best in Figure 8 because it cannot move out of that position on account of interposition of the flat face 80 even though the spring 68 is compressed.

After the door is shut, the latch bolt head 27 moves toward the right but the dead bolt head 50 is held in depressed position, as illustrated in Figure 1, by the strike plate. When the latch bolt head has moved to a position where the flat face 80 passes beyond the free ends of the arm 64, the spring 68 will act against the mid-portion of the blocker 60 causing it to rotate slightly in a counterclockwise direction about the end having the lugs 62 until the blocker comes to rest with the free ends of the arms 64 behind the inside face 43 of the latch bolt head. This is the position illustrated in Figures 1 and 7. In that position should an attempt be made by some instrument manipulated by an unauthorized person to push the latch bolt head 27 toward the left thereby to open the door in the event it were locked through appropriate conventional means, movement of the latch bolt head would be blocked by the blocker.

To open the door the inner operating element 11 can be rotated. Opening could also be accomplished by rotation of the outer operating element 10 if not prevented by some conventional locking device not shown. When the spindle 14 is rotated, the cam 37 is rotated and pushes against one or another of the lugs 36. This causes the actuator plate 34 to be moved from right to left, as viewed in Figure 7, even though the latch bolt head 27 remains stationary. As movement continues, the hooked portion 35, which is wide enough to reach over the raised portions 66 and 67, moves until it slides against the raised portions, thereby tending to shift the blocker 60 in a clockwise direction, as viewed in Figure 7, until it moves out to the position shown in Figure 8. In that position the outer ends of the arms 64 will be clear of the inside face 43 or, in other words, in unblocked position. As the spindle continues to be rotated the hooked portion 35 will pull against the adjacent side of the rectangular opening 30 in the latch bolt shaft and draw the latch bolt head 27 from right to left until it clears the aperture in the strike plate. After the door is opened, the spring 42 will return the latch bolt head 27 to its outermost position and at the same time the spring 68 will return the dead bolt head 50 to its outermost position.

It will be noted particularly from an inspection of Figure 7 that when the blocker is in blocking position there is a clearance between the outer ends of the arms 64 and the inner face 43. Hence some movement of

the latch bolt head will take place in a direction from right to left until it strikes the blocker. The movement, however, is insufficient to permit disengagement of the latch bolt head from the strike plate. This relationship is of importance when the spindle is rotated inasmuch as it permits sufficient travel of the hooked portion 35 of the actuator plate to engage the raised portions 66 and 67, thereby to move the blocker out of blocking position before the latch bolt head travels far enough to engage the blocker.

There has accordingly been described herein a dead bolt mechanism of a relatively simple type wherein shafts for the dead bolt, the latch bolt, latch actuator, and blocker all comprise relatively light gage plates positioned side by side, thereby to provide a compact mechanism constructed of stock materials which are relatively inexpensive. The arrangement and relationship is such, however, that the action is positive and secure.

While I have herein shown and described my invention in what I have conceived to be the most practical and preferred embodiment, it is recognized that departures may be made therefrom within the scope of my invention, which is not to be limited to the details disclosed herein but is to be accorded the full scope of the claim so as to embrace any and all equivalent devices.

Having described my invention, what I claim as new and desire to secure by Letters Patent is:

In a lock set comprising a latch bolt housing having an inner end wall, side wall means and an open outer end, a latch bolt member reciprocatably mounted in the 30 housing and protruding from the outer end, a latch bolt head at the outer end of said member and having a shoulder at the inside end, and a plate forming a shaft for the member located in the housing, the combination of a dead bolt mechanism comprising a dead bolt head lying 35

against one side of the latch bolt head and having a parallel path of reciprocation, and a dead locking blocker comprising a plate having an inner end loosely anchored in the inner end wall, means forming an outer end of the blocker lying against the dead bolt head and being tiltable between a position behind the shoulder on the latch bolt head and a position removed therefrom, a spring keeper on the dead bolt head with the axis thereof parallel to the axis of movement of the dead bolt head and spaced laterally outside the inner end of the blocker, a spring keeper on the blocker extending obliquely outwardly toward the free end of the blocker and intermediate the ends of said blocker, said last keeper being spaced from the dead bolt head, and a separate longitudinally extending compression spring in the space between the keeper on the blocker and the spring keeper on the dead bolt head, said spring having a mid-portion thereof lying against the adjacent side of the housing and a set of bosses respectively on the first identified plate and the blocker normally in engagement when the dead bolt is extended and having positions of disengagement when the dead bolt is depressed relative to the latch bolt whereby said spring is adapted to press axially against the dead bolt and obliquely against said blocker and to move said blocker to a blocking position.
